UNITED STATES PATENT OFFICE.

GEORGE W. PECK, OF ROSELLE PARK, NEW JERSEY.

PACKING AND TRANSPORTATION CARRIER, TRUNK, OR THE LIKE.

SPECIFICATION forming part of Letters Patent No. 723,784, dated March 24, 1903.

Application filed November 12, 1902. Serial No. 130,964. (No model.)

To all whom it may concern:

Be it known that I, GEORGE W. PECK, a citizen of the United States, and a resident of the borough of Roselle Park, county of Union, 5 and State of New Jersey, have invented a new and useful Improvement in Packing and Transportation Carriers, Trunks, or the Like, of which the following is a full, clear, and exact description, reference being had to the accompanying drawings, in which—

Figure 1 illustrates a perspective view of the invention as embodied in a trunk, the forwardly-presented corner of which has been broken away to disclose the interior construction which embodies the invention. Fig. 2 is a sectional plan view of one corner of the trunk or carrier. Fig. 3 is a vertical sectional view taken on the lines 3 3 of Fig. 2.

It has been customary heretofore to protect 20 fragile materials and also fragile vessels containing liquids against shock or jar during transportation and use by the employment of spring-buffers of various constructions located between the exterior case, box, or crate 25 and the interior vessel containing the fragile material or which was itself fragile. Such interior receptacles have almost invariably been substantially cylindrical in form, such as a bottle, a demijohn, or jar. Also I have 30 heretofore made an invention and procured a patent (it being No. 701,384 and dated June 3, 1902) therefor in which a square interior box or crate was protected exteriorly by another stronger box or crate, the prevention 35 against shock or jar being provided by spring-buffers interposed between them. In all such prior constructions, however, the spring-buffers have been permanently connected to the exterior box or crate, and, moreover, be- 40 cause the inner receptacle has been square or angular in outline there have necessarily been two buffers at each side of each angle or corner in order to afford the requisite protection against shocks coming in different direc- 45 tions.

Under my present invention (which may be beneficially employed in the manufacture of trunks and is therefore so illustrated) in order that fragile goods or personal effects may 50 not be injured during transit I have devised an altogether new construction under which the spring-buffers are permanently attached

to the interior case or box instead of to the interior corner of the outer case or box, and the buffer in its operation has a diagonal outward movement at an angle of substantially 55 forty-five degrees to each side of the interior receptacle instead of there being two buffers at each corner moving inwardly and at directly right angles to the plane of the respective sides upon which they are attached, as in former constructions. In this way it will be observed I secure several very important advantages: First, the economy in construction is reduced practically one-half; second, 60 the space required for a single buffer placed directly at the corner of the interior tray or box and having a diagonal projection is materially less (not quite one-half) than that required in the old constructions; third, under 65 my construction the rigid bar of the buffer serves also as the corner brace or post for the interior receptacle; fourth, the appearance is very much neater and more finished than where double the number of buffers are em- 70 ployed. 75

Having thus briefly recited some of the differences between my present invention and the prior art, I proceed to describe it in detail, as follows:

A illustrates the exterior box or casing. It is or may be provided with locks, hinges, a lid, and strengthening bands or ribs, as usual.

B is an interior box, crate, or case, the size of which may be substantially that of the exterior box or casing, or it may be smaller, thus permitting the use of trays. If trays are used, they may be provided with the same cushioning appliances as those about to be described. A single description, therefore, 80 will serve for all.

C is a corner brace or bar, which may beneficially extend from the bottom of the interior box or casing to the top of the sides thereof, and to this bar there are fastened the side 85 pieces of the interior case in any suitable manner. Thus it will be seen the bar C constitutes the corner-piece or strengthening-block for the interior case and likewise serves as the rigid bar for the buffer.

D is the movable or spring-actuated bar of the buffer. It is preferably rounded off somewhat or beveled at its lower end, as shown at E, whereby smooth and easy insertion of 90 95 100

the inner case within the outer one is secured, and if at any time it should be desirable to remove and then replace the inner case such replacement may be accomplished 5 with greater ease.

5 F F are pintles or headed pins fastened in the bar D, encircled with springs G and provided with heads H. The heads move through the recess I, made in the rigid bar C.

10 K K are little cushions of rubber, which I prefer to fasten on the bottom of the inner receptacle B, so that it may be resiliently supported against the bottom of the exterior box or casing, and K' K' are similar rubber 15 cushions, which may be beneficially employed at the ends and sides of the inner receptacle and which at these places are preferably so short that they will not normally touch the sides of the exterior box or casing; but in 20 the event of excessive compression coming upon the corner-buffers they will be momentarily brought in contact therewith as auxiliary cushioning devices.

25 The operation of the construction is as follows: The goods within the interior receptacle B will be cushioned against fracture incident to shock or jar by the yielding or cushioning action of the corner-buffers. When the strain comes upon them, the springs G 30 will collapse, causing the heads H of the pintles F to slide to a greater or less extent through the recess I in the rigid corner-brace C, and if excessive shock or jar occurs, then the auxiliary buffers K' will be brought into 35 action momentarily for the relief of the contents.

It will be noted that the construction is 40 relatively inexpensive and compact, and that by reason of the buffers being located at the corners of the interior receptacle and constructed in such manner that the inner bar of the buffer is rigid and the outer bar is the inovable one, and also owing to the fact that the side boards or pieces of the inner receptacle B are cut away at the very corner, there is considerable space afforded within 45 which the spring-buffers may act, whereas if the buffers had been doubled, one at each side of the corner, the inner receptacle would 50 have to be very much reduced in size.

It will be obvious to those who are familiar 55 with this art that somewhat extensive modifications may be made in the construction of the invention—that is to say, springs of a variety of forms may be employed instead of the spiral springs G, and even if spiral springs be employed they need not necessarily encircle the pintles H, nor is it essential that the pintles be employed. A single bar of wood 60 may be so fashioned, either by sawing away portions of it or by bending it over at the top or bottom, as that one part shall serve the purposes of the rigid bar B or be attached to a part serving that purpose and the other 65 part may serve the purpose of the movable parts or bars, other parts of the same piece acting resiliently or as springs between the

two. Also it is not essential that there be a separate and distinct piece to act as the movable corner-post, because one part of the elastic or resilient device may be so fashioned as to serve the purpose of the corner bar or post. I prefer, however, the construction shown, because, all things considered, it is the most reliable, convenient, and handsome construction at present known to me. Also it is not essential that the corner-buffers be in one piece or in the form of a single structure extending vertically up each corner of the inner receptacle. They may be made of two or 80 more pieces and disposed as preferred.

My invention may be employed in a variety of structures, such as trunks, fruit-carriers, egg-carriers, and generally receptacles for the transportation of fragile articles.

Having described my invention, I claim—

1. A carrier having an outer box or casing and an inner receptacle, buffers located at the corners of the inner receptacle each embodying a stationary part to which the sides of the inner receptacle are permanently attached and whereby they are supported and a movable part elastically supported upon said stationary part on the outside of the inner receptacle adapted to engage in the adjacent corner of the box or casing proper.

2. A carrier having an outer box or casing and an inner receptacle, buffers located at the corners of the inner receptacle, each embodying a part which is rigidly attached to 100 said corner, an elastically-supported part on the outside of the inner receptacle adapted to engage with the adjacent corner of the exterior box or casing and auxiliary springs or cushions which are called into action in the 105 event of excessive movement of the said corner-buffers.

3. A carrier having an outer box or casing and an inner receptacle, buffers located at the corners of the inner receptacle, each 110 embodying a vertically-extending bar which constitutes the corner of the inner receptacle and to which its side pieces are fastened somewhat back from the corner and an elastically-supported part on the outside of the 115 inner receptacle supported by said vertically-extending bar and adapted to engage with the adjacent corner of the exterior box or casing.

4. A tray or inner receptacle for carriers 120 comprising essentially a bottom and sides, the corners whereof are secured by means of a vertically-extending bar to which the side pieces are fastened somewhat back from the point of their juncture and an exterior part 125 elastically supported upon said corner-bar.

In testimony whereof I have signed my name to this specification in the presence of two subscribing witnesses.
